UNITED STATES PATENT OFFICE.

HERMANN HILL, OF WEST HAVEN, CONNECTICUT.

MACHINE FOR EXPANDING CUT AND CORRUGATED METAL.

No. 919,166.

Specification of Letters Patent.

Patented April 20, 1908.

Application filed October 28, 1908. Serial No. 459,869.

To all whom it may concern:

Be it known that I, HERMANN HILL, a subject of the Emperor of Austria-Hungary, and a resident of West Haven, in the county 5 of New Haven and State of Connecticut, have invented a new and Improved Machine for Expanding Cut and Corrugated Metal, of which the following is a specification.

This invention relates to mechanism for 10 expanding or opening sheet metal after it has been cut and corrugated in a way to permit of the expansion of the metal or opening of the meshes therein without stretching the metal and without a contraction of the sheet 15 in the direction of the cuts to compensate for or permit the expansion in the other direction.

In preparing metal for treatment by a 20 machine made in accordance with my present invention the metal has first formed therein two series of alternatingly interrupted cuts leaving series of alternating keys at the points where the cuts are interrupted. The metal is also corrugated in such a way that 25 the conformation of the corrugations will substantially correspond to the contour of a transversely arranged series of bars in the expanded metal with the connecting keys between them, whereby a sheet of such cut 30 and corrugated metal may be expanded by forcing every other row of such transversely arranged bars longitudinally away from the sheet in the direction of the expansion and bending every intermediate series of trans- 35 versely arranged bars with their connecting keys in a direction opposite to that in which they lie in the cut and corrugated metal, in order that they may form a series of connecting bars oppositely disposed to the first 40 named series.

In carrying out my invention, I provide a relatively fixed form for supporting the metal, the conformation of which is adapted to receive the corrugated metal and support 45 the same, and in connection with such a support I provide a reciprocating form having members adapted to engage successive transversely arranged series of keys and preferably the upper ones in such a cut and corrugated sheet and thus force every other transversely arranged series of bars away from the sheet in the direction of the expansion and simultaneously bend every intermediate set of bars in an opposite direction from that 50 in which they lie in the cut and corrugated sheet. Feeding mechanism is also provided

for properly feeding the sheet and a part of the reciprocating expanding mechanism is adapted to control the longitudinal feed of the sheet in such a way that the sheet may 60 be fed by means of weights or springs or any like device and the amount and the time of such feed is controlled by the arrangement of the engaging members of the expanding mechanism.

The accompanying drawings illustrating 65 a machine made in accordance with my invention are as follows:—

Figure 1, is a side view. Fig. 2, is a partial 70 rear elevation with a part of the middle of the machine removed and with parts of the expanding plates also removed to show the construction and arrangement thereof. Fig. 3, is a detail view of the means for returning 75 the reciprocating expanding mechanism to its initial position. Fig. 4, is an end view of the expanding forms and with a part of the sheet of metal in place to be acted on thereby. Fig. 5, is a rear face view of the lower 80 and the first two upper expanding forms as seen in Fig. 4, and shows a part of an expanded sheet. Fig. 6, is a view similar to Fig. 4, but with the parts in a different position and shows part of the sheet as expanded 85 thereby. Fig. 7, is a top view of the cut and corrugated metal before it is expanded and Fig. 8, is an end view, projected horizontally to the right from Fig. 6, of a part of a sheet 90 of the metal with a portion thereof expanded downwardly.

Similar letters refer to similar parts throughout the several views.

Referring to the drawings, for supporting 95 the operating parts of my machine, I make use of a frame work comprising vertical standards C connected at their upper ends longitudinally of the machine by cross bars c and transversely of the machine by cross bars c¹ and near their lower ends by longitudinally disposed cross bars c² and transversely disposed cross bars c³. Bolted to the cross bars c are seen the vertically disposed standards D, one at each side of the machine, between which is secured the cross plate H and the bed piece T. The bed piece T has a downwardly extending flange portion t and bracing webs t¹ for stiffening the same. The cross plate H has suitable reinforcing flanges h thereon as indicated in Fig. 1 and in dotted lines in Fig. 2. On the side of the plate H 100 toward the observer in Fig. 2, being the right hand side in Fig. 1, are secured guiding plates 105

110

o, between each pair of which there is arranged to be reciprocated vertically the cross heads *O* carrying at their upper ends revoluble rollers *r* arranged to be engaged by the cams *R* on the shaft *S* which is supported in suitable bearings *F* on the plate *H* and *f* on the standards *D*. On the left hand end of this shaft as seen in Fig. 2, is a spur gear *G* intermeshing with the spur gear *g* on the shaft *s* revolvably supported at its left hand end in Fig. 2, in an out-bearing *E*, the inner end of this shaft *s* being supported in a bearing, not shown, in the standard *D* seen to the left in Fig. 2. On the shaft *s* are seen pulleys *N* and *N'*, the rotation of that one of which is rigidly secured to the shaft *s* causes the rotation of the shaft *S* in the way clearly indicated. The engagement of the cams *R* on the shaft *S* with the rollers *r* carried by the cross heads *O* secured on the rear side of the reciprocating plate *P* forces such plate *P* downwardly. Upon the outer lower edge of this plate *P* is seen the angle bar *B* carrying on its rear left hand or inner face the series of plates or forms *b*, *b*¹, *b*², *b*³ and *b*⁴ adapted to coöperate with the corresponding series of plates or forms *a*, *a*¹, *a*² and *a*³, secured in the angle of the angle plate *A* which in turn rests upon a ledge *t*² formed on the bed piece *T* as shown more fully in detail in Figs. 4, 5 and 6. The upper edge of this angle bar *A* is corrugated to conform to the under surface of the sheet of cut and corrugated metal *m* as seen thereon in Figs. 4, 5, and 6. Such a corrugated sheet is fed through the machine by the plate *U* which engages the rear edge of the sheet *m* and is secured on the ends of rods *u*, arranged to work through guides therefor *t*³ carried by the bed piece *T* and extending to and through the guide arms *y* near their left hand ends as seen in Fig. 1. The rods *u* have secured thereon the studs *v*¹ working in suitable slots seen in Fig. 1. The rods *u* have secured thereon the studs *v*¹ working in suitable slots therefor in the upper ends of the arms *V*, secured in the castings *v* on shaft *s*¹, which is revolvably supported in suitable bearings therefor carried by the arm pieces *c*². There is also secured to these castings *v* outwardly extending arms *V*¹ upon which there are adjustably secured weights *w* operating to swing the upper ends of the arms *V* forwardly or to the right as seen in Fig. 1 and carrying with them the rods *u* and the plate *U* by which the sheet of metal *m* is thus forced to the right as seen in Figs. 1, 4 and 6 when the position of the expanding mechanism permits of its being thus advanced or forced to the right, the front edge of this sheet of metal *m* being brought into engagement and forced against the plate or form *b*² as clearly shown in Fig. 4.

When the plate *P* carrying the bar *B*, with the forms *b*, *b*¹, *b*², *b*³ and *b*⁴ thereon, is forced downwardly to the position indicated in Fig.

6, that portion of the sheet *m* which extended over and to the right of the right hand edge of the plate *A* as seen in Fig. 4, a distance just equaling the width of two bars in the expanded metal of the width of one key in the expanded metal, is forced downwardly, in the manner to be explained, to form two adjacent and connected transversely arranged series of bars in the expanded metal.

For raising the plate *P* with the bar *B* thereon, after each downward stroke thereof, I make use of a series of bell crank levers each pivotally supported on a stud *l* and projecting from the plate *H*. Each such bell crank lever comprises a horizontal member *l*¹ and a vertical member *l*², the horizontal members adapted to engage the under sides of bearing blocks *p* therefor carried by the cross heads *O*, the vertically disposed members of such bell crank levers articulate at their lower ends with the connecting link *L*, the right hand end of which, as seen in Fig. 2, articulates with the upper end of the lever *L*¹ rotatably supported upon a stud or bolt projecting from the arm *d* secured to the right hand standard *D*. This lever *L*¹ has a horizontal extension *I* secured thereto on which a weight may be adjustably supported to raise the plate *P* through the mechanism already just described, after each downward stroke thereof.

It will of course be understood that it is immaterial what means are employed to operate the lever arm *I*, although I prefer as above stated to make use of a weight or spring.

Attention may now be called to the fact that Fig. 5, is drawn by horizontal projection from Fig. 4, as an aid in explaining the apparatus from the drawings.

The sheet of metal *m* rests upon the bed piece *T* and upon the angle bar *A* which is corrugated to conform to the corrugated sheet *m*. The expanding forms *b*, *b*¹, *b*², *b*³ and *b*⁴ secured in the angle of the reciprocating bar *B* and the coöoperating expanding forms *a*, *a*¹, *a*², and *a*³ are secured in the fixed angle bar *A*, all of such expanding forms are of a thickness substantially equaling the space between the cuts in the cut metal or the width of a bar in the expanded metal.

Referring to Figs. 4 and 5, starting with the sheet of metal in the position indicated in Fig. 4, the forms *b* and *b*¹, conformed as clearly indicated in Fig. 5, engage the metal *m* at the upper series of keys therein and the plate or form *b*¹ engages simultaneously the outer row of bars at all points therein while the plate *b* engages back of or to the left in Fig. 4, of the plate *b*¹ forcing the two series of bars under such plates *b* and *b*¹ downwardly against the plates *a* and *a*¹ which are formed to receive respectively the plates *b* and *b*¹ and thus form the first transversely arranged series of meshes in the expanded metal. The

bars and keys thus far lying substantially transverse to the direction of the travel of the reciprocating forms b and b' . The form b^2 serves as a limiting stop against which, 5 when the bar B is raised to its uppermost position, the metal m is fed by the mechanism already described and each time the bar B is again raised the metal m is forced again to the right and the already expanded portions 10 thereof are also forced to the right so as to come under the expanding forms b^2 and b^3 coöperating with which are the fixed forms a^2 and a^3 and by means of which, at the next 15 downward stroke of the angle bar B, the bars and the keys in that portion of the metal which was expanded by the last preceding downward stroke of the angle bar B are bent so as to present the conformation clearly indicated in Figs. 6 and 8. This operation is 20 repeated for each complete stroke of the reciprocating bar B and at the completion of each upward stroke the metal m is fed against the form b^2 and at each downward stroke the metal m under the forms b and b' 25 is expanded in the manner already described and that portion of the sheet which was expanded at the preceding operation is engaged and operated upon by the expanding forms b^2 and b^3 and the forms a^2 and a^3 coöperating therewith to properly bend the bars 30 and keys in the already expanded metal m^1 obliquely downward and forward at each 35 operation of the bar B.

In operating my machine, the metal m is 35 inserted between the plate U and the expanding forms b^2 , when the bar B is at its uppermost position, by drawing the plate U to the left in Figs. 1, 4 and 6 sufficiently to permit the sheet to be inserted on the bed piece 40 T and to the right of such plate U, then by means of power applied to the driving pulleys of the machine the plate P with the bar B thereon is caused to be reciprocated in the manner already clearly described. The 45 metal is expanded one mesh at a time at each reciprocation of the plate P, and at each such reciprocation in that portion of the metal expanded at the last preceding reciprocation, the bars and keys are bent to lie obliquely as 50 already described and clearly indicated in Figs. 6 and 8.

It is believed that from the foregoing description the construction and method of operating my machine are such as to call for 55 no further explanation herein. I may add however, that the expanding form b^4 helps to keep the already expanded and formed-up metal in shape by engaging the rear series of bars of succeeding meshes and forcing the 60 same downwardly at each downward stroke of the bar B.

What I claim is:—

1. In a device for the purpose described, a bed adapted to receive and support a sheet 65 of cut and corrugated metal and a relatively

reciprocating element carrying members adapted to engage successively upper transversely arranged series of keys presented thereto and force such keys away from their normal positions in the cut and corrugated sheet in straight lines distances equaling the length longitudinally of a mesh in the expanded metal and in so doing to force each rear pair of bars connected to the keys in each such series in a direction opposite to that in which they lie in the cut and corrugated sheet.

2. In a device for the purpose described, a bed adapted to receive and support a sheet of cut and corrugated metal and a relatively reciprocating element carrying members adapted to engage successively upper transversely arranged series of keys presented thereto and force such keys away from their normal positions in the cut and corrugated sheet in straight lines distances equaling the length longitudinally of a mesh in the expanded metal and in so doing to force each rear pair of bars connected to the keys in each such series in a direction opposite to that in which they lie in the cut and corrugated sheet, such relatively reciprocating element carrying other members adapted to successively engage the bars surrounding succeeding transversely arranged series of meshes when thus forced to their proper positions in the expanded metal and incline them relatively to the plane of the travel of such relatively reciprocating expanding members.

3. In a device for the purpose described, a bed adapted to receive and support a sheet of cut and corrugated metal and a relatively reciprocating element carrying members adapted to engage successively upper transversely arranged series of keys presented thereto and force such keys away from their normal positions in the cut and corrugated sheet in straight lines distances equaling the length longitudinally of a mesh in the expanded metal and in so doing to force each rear pair of bars connected to the keys in each such series in a direction opposite to that in which they lie in the cut and corrugated sheet, such relatively reciprocating element carrying other members adapted to successively engage the bars surrounding succeeding transversely arranged series of meshes when thus forced to their proper positions in the expanded metal and incline them relatively to the plane of the travel of such relatively reciprocating expanding members and means for intermittently feeding the sheet of the cut and corrugated metal to such expanding mechanism distances equaling the length longitudinally of the sheet of the keys in such transversely arranged series thereof.

4. In a device for the purpose described, a bed adapted to receive and support a sheet 130

- of cut and corrugated metal and a relatively 5 reciprocating element carrying members adapted to engage successively upper transversely arranged series of keys presented thereto and force such keys away from their 10 normal positions in the cut and corrugated sheet in straight lines distances equaling the length longitudinally of a mesh in the expanded metal and in so doing to force each 15 rear pair of bars connected to the keys in each such series in a direction opposite to that in which they lie in the cut and corrugated sheet and means for intermittently feeding the sheet of cut and corrugated metal 20 to such expanding mechanism distances equaling the length longitudinally of the sheet of the keys in such transversely arranged series thereof.
5. In a device for the purpose described, a bed adapted to receive and support a sheet of cut and corrugated metal and a relatively 25 reciprocating element carrying members adapted to engage successively upper transversely arranged series of keys presented thereto and force such keys away from their 30 normal positions in the cut and corrugated sheet in straight lines distances equaling the length longitudinally of a mesh in the expanded metal and in so doing to force each 35 rear pair of bars connected to the keys in each such series in a direction opposite to that in which they lie in the cut and corrugated sheet; means for intermittently feeding the sheet of cut and corrugated metal to 40 such expanding mechanism distances equaling the length longitudinally of the sheet of the keys in such transversely arranged series thereof, such relatively reciprocating element carrying members adapted to limit the 45 amount of each such forward advance of the sheet of cut and corrugated metal.
6. In a device for the purpose described, a bed adapted to receive and support a sheet of cut and corrugated metal and a relatively 50 reciprocating element carrying members adapted to engage successively upper transversely arranged series of keys presented thereto and force such keys away from their 55 normal positions in the cut and corrugated sheet in straight lines distances equaling the length longitudinally of a mesh in the expanded metal and in so doing to force each rear pair of bars connected to the keys in each such series in a direction opposite to that in which they lie in the cut and corrugated sheet, such relatively reciprocating element carrying other members adapted to successively engage the bars surrounding succeeding transversely arranged series of meshes when thus forced to their proper 60 positions in the expanded metal and incline them relatively to the plane of the travel of such relatively reciprocating expanding members; means for intermittently feeding the sheet of cut and corrugated metal to 65 such expanding mechanism distances equaling the length longitudinally of the sheet of the keys in such transversely arranged series thereof, and such relatively reciprocating element carrying members adapted to limit the 70 amount of each such forward advance of the sheet of cut and corrugated metal.
7. In a device for the purpose described, a bed adapted to receive and support a sheet of cut and corrugated metal and a relatively 75 reciprocating element carrying members adapted to engage successively upper transversely arranged series of keys presented thereto and force such keys away from their 80 normal positions in the cut and corrugated sheet in straight lines distances equaling the length longitudinally of a mesh in the expanded metal and in so doing to force each rear pair of bars connected to the keys in each such series in a direction opposite to 85 that in which they lie in the cut and corrugated sheet; such relatively reciprocating element carrying other members adapted to successively engage the bars surrounding succeeding transversely arranged series of 90 meshes when thus forced to their proper positions in the expanded metal and incline them relatively to the plane of the travel of such relatively reciprocating expanding members; means for intermittently feeding the sheet of cut and corrugated metal to 95 such expanding mechanism distances equaling the length longitudinally of the sheet of the keys in such transversely arranged series thereof, such relatively reciprocating element carrying members adapted to limit the 100 amount of each such forward advance of the sheet of cut and corrugated metal and such limiting means comprising some of such other engaging members carried by such relatively reciprocating element.
